UNITED STATES PATENT OFFICE.

BEN EACHUS, OF GALLIPOLIS, OHIO.

ARTICLE HOLDER.

Application filed May 31, 1923. Serial No. 642,594.

To all whom it may concern:

Be it known that I, BEN EACHUS, a citizen of the United States, and a resident of Gallipolis, in the county of Gallia and State 5 of Ohio, have invented certain new and useful Improvements in Article Holders, of which the following is a specification.

This invention relates in general to an article holder and more particularly to a 10 combined automobile curtain holder and tool and article carrier.

The object of the invention is to provide an article holder of this character which is well adapted to carry in compact form curtains of an automobile or similar vehicle 15 and yet maintain the same readily available and accessible while preserving the curtains safe from injury or damage, the article holder at the same time being adapted to 20 contain and house tools and various articles.

Another object is to provide an article holder of this character and having the foregoing advantages and which is at the same time of simple and durable construction reliable in use, easily handled and carried 25 and adapted to be manufactured at comparatively slight expense from materials and by means of facilities ordinarily available.

Other objects and advantages of the invention reside in certain novel features of the construction, combination and arrangements of parts which will be hereinafter more fully described and particularly pointed out in the appended claim, reference being had to the accompanying drawings 35 forming part of this specification and in which:

Figure 1 is a perspective view, illustrating the preferred embodiment of the invention;

Figure 2 is a view thereof in end elevation;

Figure 3 is a view thereof in diametrical longitudinal section, parts being shown in 45 elevation for the sake of illustration; and

Figure 4 is a view thereof in transverse section.

Referring to the drawings wherein for the sake of illustration is shown the preferred embodiment of the invention, the numeral 10 designates an open ended cylinder which may be constructed of light weight 50 sheet metal, or any suitable material which is light in weight and yet provides a suitable strong and rigid structure. At each end of the cylinder 10 an outwardly extending an-

nular flange 11 is provided and may be integral with the cylinder or otherwise suitably connected thereto. The flanges 11 and the comprehended outer periphery of the 60 cylinder provide a drum upon which the curtains of an automobile or the like may be rolled, these curtains being designated diagrammatically at C for the sake of illustration. A pair of straps 12 having buckles 13 or other suitable fastening devices are utilized to hold the curtains on the drum thus provided. With the curtains so carried on the drum they are compactly and securely packed or carried and are not liable to 65 have the celluloid portions thereof crack or otherwise injured or damaged. At the same time the curtains are quickly and readily available when it is desired to use the same.

The interior of the cylinder provides a 70 tool and article receiving space and this space is preferably divided up into compartments by means of a partition 15 of circular form which is fitted into the cylinder 10 and secured in position by means of apertured ears 16 integrally formed with the partition 15 and riveted or otherwise secured by fastening means to the cylinder 10. Closures are provided for the end of the cylinder and preferably these closures 75 comprise circular closure plates 18 hingedly connected, as at 19 to the flanges 11 at the ends of the cylinder. These two closure plates are of identical construction, and as shown each is so hinged on its flange 11 as to swing toward and away from the flange 11 and its end of the cylinder, the axis of swing being at right angles to though readily spaced 80 from the longitudinal axis of the cylinder. At a point diametrically opposite its hinged connection 19 each closure plate is provided in its periphery with a radially extending 85 notch 20. A releasable fastening device is provided for these closure plates and may comprise a swinging latch 21 pivotally connected to its flange 11 by means of a pivot pin 22 and having a finger piece 23 whereby it may be readily manipulated. When it is desired to bring the plates 20 to closed position the fastening devices are rotated so as 90 to extend outwardly from the flanges 11 to which they are pivoted and the plates 18 are then brought flush up against the flanges 11, the pivots 22 and the adjacent portions of the fastening devices 21 being accommodated in the notches 20 of the plates. With 95 the parts so positioned the latches 20 are ro-

- tated so as to engage and overlie the closure plates as illustrated in Figure 2, the pivots 22 being sufficiently long to permit of this action, and the fastening devices 21 being 5 constructed of resilient metal so as to resiliently and frictionally engage the closure plates 11. It is to be understood that the plates 11 may also be constructed of resilient metal or any other suitable material.
- 10 Handles 25 are pivotally mounted by means of straps 26 on the plates 11 and afford a convenient means for handling the article holder. These handles are rotatably mounted on the plates by strap bearings 26 15 in order to permit them to be folded flush up against the plates when not in use but preferably they include a bowed portion 25^a (See Figure 2) to facilitate gripping of the same.
- 20 With the closure plate so controlled and fastened the articles contained in the com-

partments provided within the cylinder 10 are securely housed and protected and yet may be readily taken from the compartments when needed by simple manipulation of the 25 latch or fastening device 21.

I claim:

A combined automobile curtain holder and tool and article carrier comprising a cylinder having an outwardly extending 30 annular flange at each end to provide with the comprehended outer periphery of the cylinder, a drum upon which the curtains may be rolled, the interior of the cylinder providing a tool and article receiving space, 35 a partition within the cylinder defining compartments in said tool and article receiving space, a circular closure plate hingedly connected to each annular flange, and releasable fastening means between the closure plates 40 and the flanges.

BEN EACHUS.
